CLAIM

The ornamental design for a marine surge protector, as shown and described.

DESCRIPTION

FIG. 1 is a front perspective view of a marine surge protector according to our new and ornamental design;

FIG. 2 is a front view thereof;

FIG. 3 is a rear view thereof;

FIG. 4 a left side view thereof;

FIG. 5 is a right side view thereof;

FIG. 6 is top view thereof; and,

FIG. 7 is a bottom view thereof.

The broken lines shown in the drawings are for the purpose of illustrating portions of the marine surge protector that form no part of the claimed design. The broken lines showing the cable and power connection elements in FIG. 1 are for the purpose of illustrating environmental structure and form no part of the claimed design. The dash-dot broken lines in FIGS. 1 through 7 represent boundaries of the claimed design and form no part of the claimed design.
